GAME BOARD

Ralph De Jesus, Imperial Beach, Calif.
(P.O. Box 308, New York, N.Y. 10029)

Filed Dec. 15, 1969, Ser. No. 20,517

Term of patent 14 years

Int. Cl. D21—01

U.S. Cl. D34—5

Fig. 1

FIG. 1 is a top plan view of the game board;
FIG. 2 is a side elevation thereof; and

FIG. 3 is an end elevation thereof taken from the left end of FIG. 2, other end view being similar.

I claim:

The ornamental design for a game board, as shown and described.
